UNITED STATES PATENT OFFICE.

CARL PAAL, OF LEIPZIG, GERMANY.

HYDROGENIZING OLEFINIC TERPENE DERIVATIVES.

1,210,681.

Specification of Letters Patent.

Patented Jan. 2, 1917.

No Drawing.

Application filed July 18, 1914. Serial No. 851,794.

To all whom it may concern:

Be it known that I, CARL PAAL, chemist, a subject of the King of Saxony and the German Emperor, residing at 7 Windmühlenweg, Leipzig, Kingdom of Saxony, German Empire, have invented a new and useful Improvement in Hydrogenizing Olefinic Terpene Derivatives; and I do hereby declare the following to be a full, clear, and 10 exact description of the same.

The present process for hydrogenizing olefinic terpene derivatives has the purpose, to obtain from olefinic terpene derivatives containing oxygen-hydrogen, groups (for 15 instance the alcohol-, aldehyde- or acid-group) the corresponding saturated compounds while maintaining the oxygen-hydrogen groups in unchanged state.

The process consists essentially in that the 20 olefinic terpene derivatives in presence of so called adhesion compounds of the platinum metal group are subjected in neutral medium to the action of hydrogen.

I may use as adhesion compounds of the 25 platinum metal group the colloidal metals according to C. Paal (*Berichte der Deutschen Chemischen Gesellschaft* volume 37 page 124 (1904); volume 38 page 1398 (1905); German Patent 157172).

More suitable for carrying out the process 30 are the adhesion compounds obtained by precipitating platinum metals on pulverulent, indifferent substances free of anticatalytic action, which platinum metals are retained by the pulverulent particles on behalf of the adhesion (adsorption) action, (see on such compounds *Berichte der Deutschen Chemischen Gesellschaft* volume 44 page 1013 (1911); volume 46 page 3069 (1913)). By the use of the said platinum 35 metal compounds as catalysts in the action of hydrogen one succeeds to hydrogenize olefinic terpene derivatives without formation of by-products. The olefinic terpene

40 derivatives in question with one double carbon linkage can be transformed, by transition into the single-linkage form, into the saturated compounds, while those with two double carbon bonds can be converted by 45 stages into the di- and tetra-hydroderivatives, without any change taking place in the carbinol, carboxylic or aldehyde group. In this way, according to the working 50 conditions, geraniol can be transformed into 55 citronellol (dihydrogeraniol) or tetrahydrogeraniol, linalool into di- or tetra-hydroli-

nolool, citral into citronellal (dihydrocitral) or tetrahydrocitral, geranic acid into citronellic acid (dihydrogeranium-acid) or tetrahydrogeranium acid; while the olefinic terpene derivatives containing only one double linkage, as citronellol, citronellal and citronellic acid can be transformed into their 60 saturated dihydro-compounds.

The catalysts especially suitable for my 65 process, containing as large a surface as possible, consisting of the platinum metals or their protohydroxids, may be obtained by being deposited from the aqueous solution of platinum metal salts on finely pulverulent 70 substances having with reference to their finely pulverulent state a large adhering surface. Metals specially adapted to serve as catalyst carrier are: magnesium, nickel 75 and cobalt, treated, in the form of fine powder, with a solution of a palladium- or platinum salt, the palladium or platinum being precipitated as a thin metallic coating on the powdered metal. Other suitable materials are the finely pulverulent oxides of the 80 said metals, as precipitated magnesium hydroxid, magnesium- or calcium carbonate, which react with solutions of salts of palladium or divalent platinum, to form the protohydroxids, $Pd(OH)_2$ and $Pt(OH)_2$, the 85 latter being deposited, as a thin adherent stratum, on the powders; and finally inert, finely powdered insoluble substances, such as barium sulfate, kieselguhr, coal, wood dust, sawdust, cellulose powder and the like 90 can also serve as catalyst carriers, these being saturated with the palladio- or platino-salt solution and then treated with dilute soda solution, thus precipitating the respective protohydroxids, as thin coatings, on the 95 powders. The relative proportions between catalyst carrier and catalyst are preferably chosen so that the former contain 0.5-1% of palladium, as such or as protohydroxid, or 1-2% of platinum, also as 100 metal or protohydroxid..

Other suitable catalysts for hydrogenizing olefinic terpene derivatives with hydrogen are the colloidal adhesion platinum metals prepared according to the Paal process 105 in using sodium protalbinate (*Berichte der Deutschen Chemischen Gesellschaft* volume 37, page 124 (1904); volume 38, page 1398 (1905)). The said compounds contain the metals only in a very finely 110 divided state. The last named modification of my process by using the colloidal com-

pounds according to Paal is more expensive, than the use of the adhesion compounds on pulverulent substances, because in the separation of the reaction products the colloid must be precipitated by acid, in which operation the colloid is transformed into the irreversible gel. The acid may also have a transforming action on the half hydrogenized olefinic terpene derivatives. Because, however, the hydrogenizing process itself is carried out in a neutral medium and the acid is added only after the finished reduction, one is able to reduce the transforming action of the acid to a minimum in avoiding the use of a surplus of acid. For these reasons it is even possible to obtain good technical results in using the colloids according to Paal.

The use of catalysts in which the platinum metals have been imparted to as large surface as possible either by adhesion on pulverulent substances or by transformation in the colloidal state according to the quoted method of Paal presents furthermore the advantages that the catalyst can be separated from the reduction product, simply and without loss, by filtration; and also that only very small quantities of the expensive platinum metals are required.

One part of palladium or two parts of platinum will suffice to reduce a thousand-fold quantity of an olefin terpene derivative. The process is also capable of being carried out with still smaller quantities of catalyst, though in such case it takes more time, the velocity of the reaction depending on the quantity of the catalyst, and also, to a smaller extent, on the nature of the terpene derivatives, the doubly unsaturated forms of which are more easily and quickly reduced than those which have only one double carbon linkage. The reduction proceeds at ordinary temperature and atmospheric pressure, though a positive pressure of 2-4 atmospheres of hydrogen has an accelerative effect on the process, without, however, being essential. The liquid olefinic terpene alcohols and aldehydes are also hydrogenized without the application of any diluent, though it has been found advantageous to dilute them with a multiple volume of methyl- or ethyl alcohol.

In using colloidal platinum metals according to Paal aqueous solutions of the same are mixed with the alcoholic solution of the terpene derivative to be hydrogenized. Substances with an anticatalytic action, such as many metals and their compounds, for example lead, zinc, and the like; also carbon disulfid, chloroform, volatile compounds of arsenic and phosphorus, sulfureted hydrogen and mineral acids; must be avoided. The hydrogen used must also be free from anticatalytic constituents.

One has already proposed to use plati-

num black in hydrogenizing terpene derivatives (Willstätter, *Berichte der Deutschen Chemischen Gesellschaft*, volume 41, page 1475). In using platinum black one does however not succeed in maintaining the oxygen hydrogen group in unchanged state, whereas hydrocarbons are formed in a high amount. For other hydrogenizing processes one has used palladium chlorid (American Patent 1063746 Skita) or solid platinum salts (American Patent 1023753 Paal). In this way however it is impossible to hydrogenize the olefinic terpene derivatives, because in the hydrogenizing process acid is liberated which has a decomposing or transforming action on olefinic terpene derivatives.

Examples.

I. Progressive reduction of citral, geraniol, and linalool, to the corresponding dihydrocompounds.—For the semi-reduction, 1000 parts of one of the above named, freshly distilled, doubly unsaturated alcohols or aldehydes are mixed with a 7-8 fold volume of methyl- or ethyl alcohol (referred to the volume of the terpene derivative), whereupon 1 part—or if the reduction is desired to be effected very quickly, 2 parts—of palladium, or alternatively 2 or 4 parts of platinum, are added in the form of one of the catalysts mentioned above. Nevertheless, as already stated, the reduction can also be carried on with smaller quantities of palladium or platinum, with a longer expenditure of time.

Palladium protohydroxid or platinum protohydroxid deposited on finely powdered calcium carbonate, has been found specially effective, used either direct or after careful reduction with hydrogen in the cold. The mixture is next placed in a closed vessel, taking care to prevent contact with any anticatalytic metals; and the amount of hydrogen required for the semi-reduction is introduced, at the ordinary temperature and with constant stirring, whereupon the process is stopped at once. The reduction is still more rapid when performed in an autoclave provided with stirring mechanism and a pressure gage, the vessel being evacuated, to remove the air, when charged with the catalyst and the substance to be reduced, whereupon hydrogen is admitted under a positive pressure of 2-4 atmospheres, the stirrers are set in operation, and the reduction is stopped when the fall in pressure, indicated by the gage, shows that the calculated quantity of hydrogen for performing the semi-reduction, has been consumed. The semi-reduction of the doubly unsaturated geranic acid, $C_{10}H_{16}O_2$, to dihydrogeranic acid $C_{10}H_{18}O_2$, (inactive citronellic acid) is effected in the manner already described, with the slight modification that, in order to

prevent esterification, use is made of either the freshly distilled, undiluted acid, or else of the said diluted with a multiple volume of aqueous alcohol, with palladium protohydroxid, $\text{Pd}(\text{OH})_2$, or platinum protohydroxid, $\text{Pt}(\text{OH})_2$, as catalyst, which, however, in view of the fact that the acid acts on calcium carbonate, are precipitated, not on this latter substance, but on a chemically inert catalyst carrier, for example barium sulfate, the precipitated $\text{Pd}(\text{OH})_2$ or $\text{Pt}(\text{OH})_2$ being reduced with hydrogen before use. $\text{Pd}(\text{OH})_2$ or $\text{Pt}(\text{OH})_2$ precipitated on calcium carbonate can, however, also be used, after previous reduction to metal by hydrogen, provided the geranic acid be employed in the form of an aqueous solution of its alkali salt. The reaction products are isolated in known manner. For the purpose of purification they are distilled in a partial vacuum. In this way there is obtained from citral ($\text{C}_{10}\text{H}_{16}\text{O}$), dihydrocitral — inactive citronellal — ($\text{C}_{10}\text{H}_{18}\text{O}$): boiling point at 10 mm. = 79.81° ; $D_{4^\circ}^{15} = 0.8535$. Geraniol ($\text{C}_{10}\text{H}_{18}\text{O}$) furnishes dihydrogeraniol — inactive citronellol — ($\text{C}_{10}\text{H}_{20}\text{O}$): boiling point at 10 mm. = 99° ; $D_{4^\circ}^{15} = 0.8488$; melting point of the dihydrogeraniol-pyroracetate-semi-carbazone = $112-113^\circ$ (Bouveault, *Chem. Centr. Blatt*, 1904, II, 440, m. p. 112°). Linalool ($\text{C}_{10}\text{H}_{18}\text{O}$) furnishes dihydrolinalool ($\text{C}_{10}\text{H}_{20}\text{O}$): boiling point at 15 mm. = $92-93^\circ$; $D_{4^\circ}^{15} = 0.8579$. Phenylurethane of the dihydrolinalool, m. p. 60° . Geranic acid ($\text{C}_{10}\text{H}_{16}\text{O}_2$) furnishes dihydrogeranic acid ($\text{C}_{10}\text{H}_{18}\text{O}_2$) (inactive citronellic acid): b. p. 9 mm. = $139-131^\circ$; $D_{4^\circ}^{15} = 0.9277$.

II. Complete reduction of the olefinic terpene alcohols and aldehydes. — When the complete reduction of the olefinic terpene alcohols and aldehydes is in question, the employment of previously calculated quantities of hydrogen is superfluous, because the process ceases when the carbon double linkages in the molecules of the olefinic terpene derivatives have passed into the simple form. Under the working conditions stated, no further reduction takes place. The work is carried on in the way detailed in Example I. The complete reduction of the doubly unsaturated geranic acid $\text{C}_{10}\text{H}_{16}\text{O}_2$ and the simply unsaturated citronellic acid $\text{C}_{10}\text{H}_{18}\text{O}_2$, to the completely saturated, inactive tetrahydrogeranic acid $\text{C}_{10}\text{H}_{20}\text{O}_2$, (inactive dihydrocitronellic acid) or to the optically active dihydrocitronellic acid, $\text{C}_{10}\text{H}_{20}\text{O}_2$ is also effected in the manner given in Example I, with the difference that the hydrogen is allowed to act until saturation is complete. By filtering them off from the catalyst, which can then be used over again, the reduction products are obtained in quantitative amount. They are isolated in known

manner, and purified by distillation in a partial vacuum. In this way, citral, $\text{C}_{10}\text{H}_{16}\text{O}$, and dihydrocitral (citronellal) $\text{C}_{10}\text{H}_{18}\text{O}$, furnish tetrahydrocitral $\text{C}_{10}\text{H}_{20}\text{O}$, b. p. 16 mm. = $87-88^\circ$; $D_{4^\circ}^{15} = 0.831$. Geraniol, $\text{C}_{10}\text{H}_{18}\text{O}$, and dihydro-geraniol $\text{C}_{10}\text{H}_{20}\text{O}$ furnish tetrahydro-geraniol, $\text{C}_{10}\text{H}_{22}\text{O}$ b. p. 18 mm. = $112-113^\circ$; $D_{4^\circ}^{15} = 0.8329$. Linalool, $\text{C}_{10}\text{H}_{18}\text{O}$, and dihydro-linalool, $\text{C}_{10}\text{H}_{20}\text{O}$, furnish tetrahydro-linalool, $\text{C}_{10}\text{H}_{22}\text{O}$: b. p. 15 mm. = 89° ; $D_{4^\circ}^{15} = 0.8327$; $(\alpha)_D = -0.78$. Geranic acid, $\text{C}_{10}\text{H}_{16}\text{O}_2$, furnishes tetrahydrogeranic acid $\text{C}_{10}\text{H}_{20}\text{O}_2$; b. p. 10 mm. = $133-134^\circ$; $D_{4^\circ}^{15} = 0.899$. Citronellic acid furnishes dihydrocitronellic acid. $\text{C}_{10}\text{H}_{20}\text{O}_2$, (optically active tetrahydro-geranic acid): b. p. 9 mm. = 133° ; $(\alpha)_D 19^\circ = +4.58$; $D_{4^\circ}^{15} = 0.895$.

In comparison with the previously known processes mentioned above, and with that of German Patent 230724, the process exhibits the following technical advantages: (1.) Only very small quantities of the expensive palladium or platinum, acting as the hydrogen carrier are required; (2.) The reduction product can be separated from the catalyst in the simplest manner, by filtration, not even a trace of the catalyst is lost, and the latter is fit for use over again without further treatment; (3.) In the case of doubly unsaturated compounds the reduction may be partial (semi-) or complete, as desired; (4.) The process goes on quantitatively at the ordinary temperature, without the formation of by-products; (5.) The reduction occurs in a perfectly neutral solution so that the transpositions and condensations to which the olefinic terpene derivatives are liable under the influence of alkalies or acids cannot take place.

I claim:

1. The process for preparing saturated aliphatic terpene derivatives containing oxygen-hydrogen groups which consists in mixing olefinic terpene derivatives containing oxygen-hydrogen groups with adhesion compounds of the platinum metal group free of acid and introducing hydrogen at ordinary temperature in a neutral medium into the said mixture.

2. The process for preparing saturated aliphatic terpene derivatives containing oxygen-hydrogen groups which consists in mixing olefinic terpene derivatives containing oxygen-hydrogen groups with adhesion compounds of the platinum metal group free of acid and introducing hydrogen at ordinary temperature under higher than atmospheric pressure in a neutral medium into the said mixture.

3. The process for preparing saturated aliphatic terpene derivatives containing oxygen-hydrogen groups which consists in dissolving olefinic terpene derivatives containing oxygen-hydrogen groups in organic

solvents, mixing the said solution with adhesion compounds of the platinum metal group free of acid and introducing hydrogen at ordinary temperature in a neutral medium into the said mixture.

4. The process for preparing saturated aliphatic terpene derivatives containing oxygen-hydrogen groups which consists in mixing olefinic terpene derivatives containing oxygen-hydrogen groups with substances of the platinum metal group free of acid previously deposited on different pulverulent substances and introducing hydrogen at ordinary temperature into the said mixture.

5. The process for preparing half saturated aliphatic terpene derivatives containing oxygen-hydrogen groups which consists in mixing olefinic terpene derivatives containing oxygen-hydrogen groups and two double linkages of carbon with adhesion compounds of the platinum metal group free of acid and introducing hydrogen only in sufficient amount for hydrogenizing one double linkage of carbon at ordinary temperature in a neutral medium into the said mixture.

6. The process for preparing half saturated aliphatic terpene derivatives containing oxygen-hydrogen groups which consists in mixing olefinic terpene derivatives containing oxygen-hydrogen groups and two double linkages of carbon with adhesion compounds of the platinum metal group free of acid and introducing hydrogen only in sufficient amount for hydrogenizing one double linkage of carbon at ordinary temperature under higher than atmospheric pressure in a neutral medium into the said mixture.

pressure in a neutral medium into the said mixture.

7. The process for preparing half saturated aliphatic terpene derivatives containing oxygen-hydrogen groups which consists in dissolving olefinic terpene derivatives containing oxygen-hydrogen groups and two double linkages of carbon in organic solvents, mixing the said solution with adhesion compounds of the platinum metal group free of acid and introducing hydrogen only in sufficient amount for hydrogenizing one double linkage of carbon at ordinary temperature under higher than atmospheric pressure in a neutral medium into the said mixture.

8. The process for preparing half saturated aliphatic terpene derivatives containing oxygen-hydrogen groups which consists in dissolving olefinic terpene derivatives containing oxygen-hydrogen groups and two double linkages of carbon in organic solvents, mixing the said solution with substances of the platinum metal group free of acid previously deposited on indifferent pulverulent substances and introducing hydrogen only in sufficient amount for hydrogenizing one double linkage of carbon at ordinary temperature under higher than atmospheric pressure into the said mixture.

In testimony whereof, I have signed my name to this specification in the presence of two subscribing witnesses.

CARL PAAL.
